UNITED STATES PATENT OFFICE.

DONALD B. BECKER, OF WATERVLIET, NEW YORK, ASSIGNOR TO GEO. P. IDE & CO., OF TROY, NEW YORK.

SOFT COLLAR.

1,276,480.

Specification of Letters Patent. Patented Aug. 20, 1918.

Application filed May 16, 1917. Serial No. 168,992.

To all whom it may concern:

Be it known that I, DONALD B. BECKER, a citizen of the United States, residing at Watervliet, in the county of Albany and State of New York, have invented certain new and useful Improvements in Soft Collars, of which the following is a specification.

Manufacturers receive many complaints, from time to time that in the two part, or outer fold, soft collar, when the necktie is placed between the band and the top fold, the top fold rolls up, thereby producing an unnatural and untidy appearance and shape to the front of the collar which is very objectionable.

Many expedients have been resorted to in an effort to stiffen a soft collar so that it may have somewhat the pleasing appearance of a stiff collar, and at the same time possess the advantages of a soft collar. Some of these expedients consist of incorporating or inserting various widths of strips of celluloid, placed in pockets made in either the top fold or neck band portion, or inner fold; and said stiffeners being adapted to be removed when the collar is sent to the laundry, but it is well known that each plan has its serious objections. These inserts or stiffeners are, as a rule, noticeable when placed in the outer fold of the collar and the soft material of the collar "breaks" at the marginal edges of the stiffener. Further; the collar is not soft and pliable in the area of the stiffener.

The object of my invention is to incorporate into the outer or top soft fold of a collar, in the process of manufacture, an unremovable stiffening material that is not affected by the laundrying process and maintains its rigidity at all times, said material being known as haircloth, but if in the future a cheaper or more available material is found I would not depart from the spirit of my invention by availing myself of its use.

In the drawings:—

Figure 1 is a perspective view showing the collar as it will appear when worn with a necktie, the stitches securing the haircloth not showing in the finished product.

Fig. 2 is a plan view of a collar laid out flat, the outer and inner folds being extended in the same plane.

Fig. 3 is a sectional view on the line 4—4 55 Fig. 2.

Fig. 4 is a detail view of a collar partially completed, looking at the outer face of the neck band and the inner face of the outer fold, one of the plies of the outer fold being 60 folded back to show the stiffener stitched to a ply of the outer fold.

The reference numeral 1 designates the neck band or inner fold and 2 the outer fold of the collar; the neck band having 65 the usual button holes 3 and 4.

It is well known that on all soft collars underneath one side of the top fold there is sewed on to the neck band a button, clasp, or the like, for the purpose of buttoning the 70 opposite end of the band top thereto.

Now said sewed on button, and other like permanently secured devices are very objectionable for they are apt to come off at any time and serious discomfornture result, and 75 they are especially liable to break off in the laundry, and not only that it is a nuisance in the ironing process. Therefore it is one of the purposes of my invention to remedy this evil and do away with the annoyance 80 of a sewed on button, a clamp or the like. No claim is made herein for this feature as it will be claimed in another application filed February 14, 1918, Serial No. 217,106.

The neck band is also provided near its 85 top margin with two holes 5 and 6, one of said button holes (5) being positioned on the neck band so that it will be concealed when the outer fold of the collar is folded down in its normal position when on the 90 neck of the wearer. The other additional button hole 6, (which is usual in collars in connection with the aforementioned sewed on button) being formed near the end of the collar band and beyond the end margin 95 of the outer fold as shown in the drawing. The button hole 5 may extend entirely through the neck band. The button hole 5 is located in the same position or point at which it has heretofore been customary to 100 attach a button, or clasp, or catch. By forming this button hole 5 the wearer is enabled to insert a button therein which button engages the button hole 6 and thereby holds the collar against separating at the 105 top of the front ends of the neck band. When the collar is to be laundried the button may be removed.

The top or outer soft fold 2 of the collar may be formed of as many plies as desired, but according to my invention the portions of the top fold of my improved collar are 5 composed of a plurality of plies, one of the plies to consist of haircloth, or its equivalent; said ply of haircloth may be of various lengths extending back into the body length of the top fold according to the essential 10 requisites of the particular style and shape of the collar made so as to perform the function of stiffening and prevention of buckling of the top fold of the collar.

The ply of the haircloth 7 is stitched, or 15 otherwise suitably secured, to one of the other plies of the top fold thereby firmly securing it in the proper position to perform its function, the front and bottom edges of the haircloth being secured to the front 20 and bottom edges of the top fold and the usual marginal stitches 8 of the collar pass through the front and bottom marginal edge portions of the haircloth so that the front and bottom edges of the outer fold at the 25 end portions are also stiffened against buckling around a necktie so that the entire area of the end portions of the collar are stiffened and there are no visible lines of demarcation between the stiffened portion 30 of the outer fold and the balance of the top fold which balance remains soft and un stiffened.

What I claim is:—

1. A soft turn down collar comprising a

neck band and an outer turned down portion, said outer portion comprising a plurality of plies of material, a ply of stiffening material of restricted area secured to the end portion of one of the plurality of plies of the outer portion, the bottom and end marginal edges of all of said plies being secured together by the usual marginal run seam.

2. A soft turn down collar comprising a neck band and an outer turned down portion, said outer turned down portion comprising a plurality of plies of material one of which plies being of comparative restricted area and of haircloth, whereby the end portions of the said outer portion is reinforced by said haircloth against buckling, and collapsing, and whereby the intermediate portion of the collar remains unstiffened.

3. A soft turn down collar comprising a neck band and an outer turned down portion, said outer portion comprising a plurality of plies, a ply of haircloth of comparatively restricted area secured between said other plies, the lower edges of the haircloth and the edge thereof adjacent the ends of the outer portion being secured to the said other plies by the usual marginal stitches of the collar, whereby the end portions of the outer fold including the bottom and end edges thereof are reinforced against buckling.

In testimony whereof I affix my signature.
DONALD B. BECKER.
